Primary Examiner—Ralf Seifert

[57] CLAIM

The ornamental design for a pocket key hook, as shown and described.

DESCRIPTION

FIG. 1 is a front perspective view of the new design complete in a vertical position, with the key ring and pull ring omitted;

FIG. 2 is a rear perspective view thereof;

FIG. 3 is a front perspective view of device placed in a horizontal manner. This view illustrates the curve formed by the two arms that holds the device in position; and,

FIG. 4 is a rear perspective view thereof.
